UNITED STATES PATENT OFFICE.

GEORGE E. REHBERGER, OF BALTIMORE, MARYLAND.

MACHINE FOR BAGGING POTATOES.

No. 821,814.

Specification of Letters Patent.

Patented May 22, 1906.

Application filed December 31, 1902. Serial No. 137,280.

To all whom it may concern:

Be it known that I, GEORGE E. REHBERGER, a citizen of the United States, residing at Baltimore, State of Maryland, have invented certain new and useful Improvements in Machines for Bagging Potatoes, of which the following is a specification.

This invention relates to new and useful improvements in bag-holders; and it is the object of the invention to produce a device of this character wherein the bags to be filled are automatically opened; and it is also an object of the invention to produce novel means in a device of this character wherein the bags are brought successively into operative position for filling.

It is also an object of this invention to present a device of this character which is held normally inoperative and is provided with means whereby the weight of the contents of a bag being filled brings the invention into operative position.

Furthermore, an object of this invention is to provide a device applicable to a potato-digger or other agricultural machine whereby the device is caused to operate when in operative position by the operation of the agricultural machine.

With the foregoing and other objects in view the invention consists in the details of construction and in the arrangement and combination of parts to be hereinafter more fully set forth and claimed.

In describing the invention in detail reference will be had to the accompanying drawings, forming part of this specification, wherein like characters denote corresponding parts in the several views, in which—

Figure 1 is a side elevation of the machine. Fig. 2 is a vertical section on the line 2 2 of Fig. 1, looking toward the rear of the machine, with the endless conveyer removed. Fig. 3 is a skeleton plan view of the rear end of the machine, showing the chutes and bags supporting tables. Fig. 4 is a horizontal longitudinal section on the line 4 4 of Fig. 1. Fig. 5 is a detail view of the mechanism for positively operating the crank mechanism. Fig. 6 is a fragmentary plan view of one of the discharging-tables, illustrating the mechanism for feeding the bags. Fig. 7 is a fragmentary vertical view of the guiding-bars of the delivery mechanism. Figs. 8 and 9 are top views of details of the delivery mechanism. Fig. 10 is a transverse section of the delivery mechanism, showing the bags ap-

plied thereto. Fig. 11 is a fragmentary end view illustrating the portion of the delivery mechanism not shown in Fig. 7. Fig. 12 illustrates a perspective view of one of the bags and its supporting-block. Fig. 13 is a section taken on the line 13 13 of Fig. 10.

In the drawings, A designates a frame of any suitable construction, and in the present instance comprising parallel side bars, a series of cross-bars connecting the side bars, and a rectangular frame A', extending vertically from the said side bars. At the front the frame A is supported by the wheels A², and at the rear the said frame is supported by the wheels A⁴, mounted on the axle-shaft A³. The axle-shaft A³ is revoluble with the wheels A⁴, and said shaft carries a gear-wheel a, which revolves therewith and meshes a gear-wheel a', which latter is carried on a horizontal shaft a², extending crosswise of the machine and supported in bearings at each side of the frame A. Mounted on the extreme ends of the shaft a² are sprocket-wheels a³.

Beneath the rectangular frame A' and extending across the machine is a horizontal shaft b, which is supported at each end in bearings on the frame A. This horizontal shaft b is provided on each end with a sprocket-wheel b' and chains b², which pass around both the sprocket-wheels a³ and b' and transmit motion to the shaft b. The extreme outer end of the shaft b carries a sprocket b³.

A suitable conveyer D is arranged near the front of the frame A and extends to the top of the frame A'. As this machine is intended more especially to be applied to a potato-digger, it is to be understood that it is the object of the conveyer to carry the potatoes dug up by the shovel F to the top of the frame A'.

Two screens I and I' are secured in any suitable manner between the vertical standards of the frame A', and one screen has position directly above the other. The uppermost screen I is a coarser mesh than the lower screen I', and the potatoes and earth fall from the conveyer and drop on the screen I, and the small potatoes will pass through the openings in this screen and fall through the mesh thereof onto the lower screen I'. A chute L² is positioned beneath the screens I and I' and serves to catch the material that sifts through the screens. Said chute L² leads to and discharges behind the conveyer D.

Two inclined chutes L L' are supported in any suitable manner and lead from the ends of the screens I I', respectively, on an incline to opposite sides of the machine or frame A. The lower ends of the chutes rest on cross-rods l², which extend crosswise of the frame A and are supported at each end by vertical standards l³. As the potatoes pass from the screens onto the chutes L L' they are conveyed to the opposite sides of the machine to be received by the bags held by the mechanism now to be described and which forms the essential feature of this invention.

15 The mechanism now to be described is duplicated—that is, there are two separate and independent chutes for discharging potatoes, and consequently there must be two bag-holding devices—and as each of these devices 20 is alike in every detail but one need be described. Above the frame A the machine is provided with a table M, which is pivotally supported near one end on the shaft b. The opposite end of the said table rests on a spiral 25 spring M', which latter is supported on a bracket M². It is to be noticed that the table M extends considerably beyond the shaft b. The table M, or its portion beyond the shaft b, carries two brackets m, which support 30 a horizontal shaft m', and this shaft carries a gear-wheel m², arranged between said brackets. On an outer end of the shaft m' is mounted a sprocket-wheel m³. A sprocket-chain m⁴ passes around the wheel m³ and also 35 around the sprocket-wheel b'', from which latter the chain is continuously driven when the machine is in motion. The sprocket-wheel b'' is fixed on the shaft b intermediate the frame and the wheel b'.

40 The vertical bars B' of the frame A' each support a hanger n. Mounted in the hanger is a horizontal crank-shaft n', having at each end a crank n². The crank-shaft n' carries a gear-wheel n³, which is in line with the gear 45 m² and at certain times meshes with said gearing and is revolved to impart motion to the crank-shaft n' of the cranks n². It will be seen that if the rear end of a table M is loaded with a filled bag of potatoes that end 50 of the table will be depressed, because the spring M' is not of sufficient strength to support a filled bag. The depression of this end of the table will raise the opposite end of the table, and with it the parts m' m² m³, carried thereby, and cause the gear-wheel m² to mesh with the gear-wheel n³, which is carried by the crank-shaft m'. As the gear-wheel m² is 55 continuously revolving the gear-wheel n³ will revolve as long as the last-named end, which 60 is the forward end, of the table remains raised or elevated. When the filled bag is removed from the rear end of the table, the spring M' will return the table to its normal position, and the gear-wheels m² and m³ will be disengaged. It may be stated that the strength 65

of the spring M' may be predetermined in order that the quantity to be held by a bag may be automatically controlled.

The bag-feeding mechanism comprises two vertical standards o, which support two 70 parallel horizontal guide-bars o' o², one above the other, and the opposing sides of said bars each have a bead or tongue o³. The bottom surface of the bar o' is provided between its ends with a plurality of inverted-V-shaped 75 notches o⁴, and at the extreme outer end the said bar is provided with two depending spring-catches c⁵. Secured to the sides of these guide-bars are brackets P, and a slide P' extends through said bracket and has a 80 sliding movement in a lengthwise longitudinal direction and parallel with the bars o' o². This slide P' is provided on its inner vertical side with a plural number of pawls P², which latter project inwardly between the guide-bars o' and o². The said slide P' is also provided near one end with a slot P³, which extends longitudinally thereof. A cross head or slide q also extends through one of the 85 said brackets P. Said cross-head slides in a 90 direction parallel with the slide P and is provided at one end with a block or head q'. This block or head q' is provided with a pawl q², which, like the pawls P², projects between the guide-bars o' and o². This cross-head q 95 is provided with a plate q³, which projects over the top of the slide P' and projects down into the slot P³ in said slide in order that the cross-head may have a limited longitudinal movement independently of the slide, so that 100 the slide P' will not move until the plate q³ has reached the end of the slot P³. A connecting-rod q⁴ connects the cross-head q with the crank n², so that when the gear-wheel n³ 105 revolves it will impart a rotary movement to the crank, and the latter in turn will transmit a reciprocating motion to the cross-head by means of the connecting-rod.

A rod r, as seen in Fig. 6, extends in a crosswise direction above the forward end 110 of the table M and at each end is provided with a block r', which rides in the space between the guide-bars o' and o², as seen in Fig. 11. This block r' is provided in its side with an opening r², and on its top the said block is 115 provided with a pawl r³, which engages the V-shaped notches o⁴ in the upper bar o'.

It will be understood that the slide P' reciprocates at the vertical side of the guide-bars o' and o² and that the pawls P² project between the said guide-bars. These pawls are disposed or spaced on the slide at equal distances from each other, and the notches o⁴ on the guide-bar o', beneath which said pawls move, are spaced apart the same 125 distance as the pawls. Now when the slide makes its forward stroke toward the front of the machine the pawl P² next in front of the block r' will ride over the vertical front edge of the said block r' and spring into the side 130

opening r^2 thereof, and when the next rearward or reverse movement of the slide takes place the pawls P^2 , engaging the blocks r' , will draw the latter back with it. The block 5 is thus moved rearwardly until its pawl r^3 engages another of the bottom notches o^4 in the guide-bar o' , by which it will be held while the slide makes a second forward movement.

The bags s are provided on opposite sides 10 with metallic blocks s' , and these blocks are provided in their sides with depressions or slots s^2 , and their tops and bottoms are each provided with grooves s^3 . These bags are supported at each side by the guide-bars o' and o^2 , and the blocks s' are fed into the spaces by each pair of bars. In feeding the empty bags rearward the pawls P^2 take in the depressions or slots s^2 , and when the slide P' is moved rearward each bag is also moved 20 rearward, and the block r' will be moved rearwardly at the same time and will hold the bags stationary while the slides P' and the pawls P^2 make their return stroke. Thus at each stroke of the slide P' all the bags are 25 moved rearwardly one notch and held in place.

When a bag has been filled and discharged and a new bag is to be put into position, it must be opened and held in that position 30 while the same is being filled. The mechanism for accomplishing this result is as follows: When the connecting-rod q^4 moves forward, it causes the cross-head q also to make a forward move, and the head q' on the end of 35 said cross-head has position in line with one of the blocks s' and the pawl q^2 in said head is in engagement with the depression s^2 in said blocks. When the cross-head is moved rearwardly, it makes a preliminary or independent movement, because the plate q^3 merely 40 slides in the slot P^3 and allows the slide P' to remain stationary. This preliminary or independent movement of the cross-head opens the bag, because the rearward block s' on the 45 bag is held by the head q' , while the forward block is held by the slide P' , which has not yet begun to move. When the plate q^3 of the cross-head reaches the end of the slot P^3 , the slide P' is then moved forward to the 50 cross-head and all the bags are moved forward one notch. The blocks s' on the open bag then have position as seen in Fig. 7 and are held by the spring-catches o^5 .

It has been explained that by the tilting of 55 the table M the gears m^2 and m^3 are made to mesh and the latter gear to be revolved, and thereby revolve the cranks n^2 . It has also been explained that the revolution of the cranks operates the bag-feeding mechanism. 60 It has also been explained that the bag-feeding slides and cross-head make one complete reciprocating movement and then wait until another bag is filled. In order to insure that a complete backward-and-forward movement 65 is made by these parts, so that the cranks

will always start from the same point, a special and simple device is provided, which will now be described.

With particular reference to Fig. 5, it will be seen that a bracket m is provided with an 70 arm t' , and the outer end of this arm carries a pin t^2 . The gear n^3 has a pin t^3 , which projects laterally therefrom, and the shaft n' , on which said gear is mounted, is provided with a bell-crank lever u , one arm of which has a 75 pawl u' , which lies in the path of the pin t^3 of the gear. A rod u^2 is pivotally connected at one end to the bell-crank lever, and the other end of said rod is pivotally connected to the free end of the lever u^3 . This latter lever is 80 pivoted at u^4 to a stationary part of the machine, such as the frame A' , and the outer end of said lever is provided with a slot v , which receives the pin t^2 . It will be remembered that the bracket m is secured to the 85 table M and moves therewith. When the bracket is lowered with the table, the slotted end of the lever u^3 is also lowered and the opposite end of said lever and the rod u^2 are raised and the bell-crank lever u caused to 90 turn in an arc of a circle. This movement of the bell-crank lever brings the pawl u' against the pin t^3 and in case the gear has not made a complete revolution revolves the said gear until the revolution of the same is completed 95 and in position to be again revolved.

Means are provided whereby the bags which have been filled are discharged, and by reference to Fig. 1 of the drawings it will be seen that the bottom of the bag s while it is 100 being filled projects beyond the end of the table M . Beneath the discharge end of the table is an endless belt T , which passes over a roller on the shaft a^2 and then over another roller t at the rear of the wheel A^4 . As the 105 table is lowered the bag s seats on the belt and is carried away and is elevated to the ground by an attendant.

Having thus described my invention, what I claim as new, and desire to secure by Letters Patent, is—

1. In a machine of the character described, the combination of a table pivoted to the frame thereof, gearing on a frame and the table, a bag-holding means carried by the table, means carried by the machine to engage the gearing of the table when said table is tilted, and suitable connections between the said means on the machine and the bag-holding means of the table to reciprocate said bag-holding means.

2. In a machine of the character described, the combination of a table pivoted to the frame thereof, gearing carried by a frame and the table, rotatable means carried by the machine comprising a crank-shaft deriving motion from the gearing when the said table is tilted, bag-holding means carried by the table to reciprocate thereon, and connections 125 between the cranks of the shaft and the bag- 130

holding means for reciprocating said bag-holding means when the crank-shaft is rotated.

3. In a machine of the character described, 5 the combination of a shaft carried by the frame, a table pivotally secured to the shaft, a suitably-mounted gear-wheel on the table, connections between the shaft and gear-wheel for driving said gear-wheel, reciprocating bag-holding means on the table, a crank-shaft mounted on the frame, connections between the crank-shaft and bag-holding means for reciprocating said bag-holding means, and a gear-wheel on the crank-shaft adapted 10 to mesh with the gear-wheel on the table when said table is tilted.

4. In combination, a pivoted table and bag-holding means carried by the table, said means comprising suitably-supported guide-bars, bags, blocks on the bags adapted to ride 20 between the guide-bars, and means engaging the blocks of the bags to move said bags forward in one direction.

5. In combination, a pivoted table and 25 bag-holding means carried by the table, said means comprising suitably-supported guide-bars, bags, blocks on the bags adapted to ride between the guide-bars, and means engaging the blocks of the bags to distend the mouth 30 of the bag and to move said bag in one direction.

6. In combination, a suitably-pivoted table, bag-holding means carried thereby comprising guides, bags, blocks on the bags working 35 within the guides, a follower working within the guides and means for imparting motion to the follower in one direction.

7. In a bag-holder, the combination of 40 guides, slides carried by the guides, a second slide arranged with relation to each of the first-named slides and adapted to operate in conjunction therewith, pawls on the slides, bags, blocks on the bags to ride within the guides, said blocks being engaged by the 45 pawls of the slides, and means for imparting reciprocatory motion to the slides, the movement of the second-named slides being independent of the first-named slides a portion of the distance of their travel.

50 8. In combination, a bag-holder comprising guides, each guide consisting of suitably-spaced bars, brackets secured to the bars, slides working within the brackets, pawls on the slides, bags, blocks on the bags sliding 55 within the guides, said blocks being engaged by the pawls of the slides, and means for reciprocating the slides.

9. In combination, a bag-holder comprising 60 suitable guides, a slide carried by each of the guides, said slide having a slot near its end, a second slide positioned with relation to the first-named slide and acting in conjunction therewith, a plate carried by the

second slide riding in the slot of the first-named slide, bags, blocks on the bags, pawls 65 on the slides engaging the blocks of the bags, and means for imparting a reciprocatory motion to the second-named slides.

10. In a bag-holder, the combination of 70 suitable guides, bags, blocks on the bags riding within the guides, a follower, means for imparting motion to the follower in one direction, and means carried by the follower operating in conjunction with the guides for preventing retrograde movement of the follower. 75

11. In a bag-holder, the combination of 80 guides, each guide comprising suitably-spaced bars, the opposing face of one of the bars being notched, bags, blocks on the bags riding within the guide, a follower riding within the guide, means for imparting motion to the follower in one direction, and a pawl carried by the follower to engage the notches of the guide to hold the follower 85 against retrograde movement.

12. In a bag-holder, the combination of 90 suitable guides, bags, blocks on the bags riding within the guides, a follower riding within the guides, slides carried by the guides, 95 means for imparting motion to the slides, and means carried by the slides for engaging the follower.

13. In a bag-holder, the combination of 95 guides, bags, blocks on the bags riding within the guides, a follower riding within the guides, the ends of the follower being notched, slides carried by the guides, pawls carried by the guides to engage the notches of the follower and means for imparting motion to the follower. 100

14. In a bag-holder, the combination of 105 guides, each of the guides comprising suitably-spaced bars, the opposing face of one of the bars being provided with notches, catches carried by the notched bar of the guide, bags, blocks on the bags riding within the guides, and means carried by the guides engaging the blocks to force the bag in one direction. 110

15. In a machine of the character described, 110 the combination of a pivoted table on the frame thereof, means for holding said table normally horizontal, bag-holding means carried by the table, means for intermittently reciprocating said bag-holding means, and additional means acting in conjunction with the first-named means for causing the complete backward-and-forward motion of the reciprocating means. 115

In testimony whereof I affix my signature 120 in the presence of two witnesses.

GEORGE E. REHBERGER.
